UNITED STATES PATENT OFFICE.

CHARLES A. TWIGG AND ANDREW G. SPINNEY, OF PORTLAND, MAINE.

SAFETY DEVICE FOR BOILERS.

Application filed July 2, 1920. Serial No. 393,590.

This invention relates to improvements in safety devices for boilers. More especially it relates to devices particularly adapted for domestic hot water service boilers and provides relief for such from excess of temperature or pressure or a combination of both.

It is common practice today to connect hot water boilers direct to the municipal supply and thereby subject them constantly to the static pressure of the main. Occasionally much higher pressures may be imposed upon the boiler, for example, the pressure due to water hammer. Faucets which can be turned from full on to full off in a half rotation of their handles cause such sudden stoppage of flow that severe water hammers occur and, because of the well nigh incompressibility of water, exert dangerous pressures on the boiler. These suddenly applied pressures may and usually do take place at ordinary boiler temperature and therefore to protect the boiler the invention provides relief from excessive pressure alone.

Under different conditions where there may be an opening in the system sufficiently large to prevent formation of any excess pressure, or where for some unaccountable reason the supply may be temporarily cut off, a very high temperature may be developed which would melt the soldered joints and cause the boiler to leak. The invention also provides two means of relief from such high temperature conditions.

But this invention goes further than simply giving relief from either pressure or temperature alone and provides other means which respond to either excessive temperature or pressure alone, or to a combination thereof and insure the safety of the boiler in case any or all of the other relief elements fail. And it is also a feature of this last mentioned means that still another safeguard is provided which in time effects a condition which necessitates a resetting of the device and thereby insures its inspection and care. This is important since the average house owner assumes that any safety device is in working condition and seldom, if ever, takes the trouble to test or inspect the same with the result that after a while the device may become inoperative and afford no protection at all. Each time a device embodying the present invention operates either in response to pressure alone, temperature alone or what is usual to both, a slight change in the relation of cer-

tain parts is effected which ultimately produces a condition that indicates the need of inspection and probable replacement of some of the parts.

The appended drawings disclose one mode in which the principles of the present invention may be applied. A safety valve is provided at the top of the boiler and arranged to open outward. Normally this valve is maintained seated by an externally applied closing pressure which can be adjusted to be overcome at any desired pressure. Below the valve, and extending well into the boiler, is a thermoresponsive member suitably anchored and having its highly expansible element arranged to exert pressure outward on the valve to overcome the aforementioned closing pressure and thereby open the valve. In case, however, the normal closing pressure is augmented by other conditions, such as an additional weight aiding it, or corrosion causing the moving parts to stick, the invention provides further relief by arranging for the strut which transmits the closing pressure to bottom upon a soft metal block in the top of the valve. In consequence under abnormal conditions where the strut could not be moved either by high pressure of the contents acting on the valve, or by pressure imposed by the expanding thermo-responsive element, the soft metal block will yield to permit relative movement between the strut and the valve and thereby unseat the latter. In fact each time the valve is raised, the natural inertia of the moving parts causes the sharp point of the strut to be forced into the soft metal block a small amount so that as the valve reseats, the strut and other moving parts applying the closing pressure are slightly nearer the valve seat. A fixed stop in the path of one of these parts finally limits the degree of approach toward the seat, and thereby in time arrests the application of the closing pressure. When this occurs, the valve will constantly leak or set up such a chattering that attention must be given it, thus insuring its inspection.

Other additional fusible plugs are provided which are ancillary to the soft metal block just mentioned but which provide still another avenue of relief.

In its preferred form disclosed herein, a device embodying the principles of the invention may be constructed as a fitting to go on the ordinary outlet of a boiler having itself a

suitable outlet for connection with the distributing pipe of the house system and another outlet leading to a drain or waste pipe. A single valve serves to cut off this latter outlet but leaves a free open passage from the boiler opening to the distributing outlet. And by a unique arrangement of parts, the several elements which are operative in connection with the different reliefs provided, are organized to exert their respective influence upon the single valve.

It is intended that the patent shall cover by suitable expression in the appended claims whatever features of patentable novelty exist in the invention disclosed.

In the appended drawings:

Figure 1 is a vertical elevation of a device embodying the present invention, and showing it attached to the discharge outlet of a boiler, the device itself being for the most part in section as on line 1—1 of Figure 2;

Figure 2 is an elevation in medial section through the body of the device with certain of the parts in full view; and

Figure 3 is a plan of a section, on line 3—3 of Figure 1, through the device.

Referring particularly to the drawings there is attached to the upper portion of a hot water boiler 1, about the outlet 2, a relief device 3 having a chamber therein with outlet 4 adapted to be connected to the distributing pipe of the house system. At substantially the level of the upper side of this outlet, the casing of the device is belled outward to form a spherical seat for a valve 5 whose lower face is also of spherical shape to fit this seat. A series of holes are provided in the valve near its edge in which are embedded fusible plugs 6. On its underside the valve has guide members 7 for positioning the valve properly on its seat and on its upper side has a hollow hub with two holes leading from the hollow through the valve. These holes and the hollow of the hub are likewise filled with soft metal preferably fusible, the latter constituting what will hereinafter be termed the block 8.

Above the valve, the chamber has a side outlet 9 for connection with a drain, and a top cover having a hole therethrough to accommodate a strut 10. The latter has a sharp pointed end that rests on the soft metal block 8. This strut extends through the cover and contacts with a lever 11, pivoted at 12 on the cover. Beyond its contact with the strut 10, the lever has a weight 13 adjustable along it to impose a predetermined force upon the strut and through it upon the valve to hold the latter upon its seat. Preferably an elongated bushing 14 is provided in the cover both to prevent leakage around the strut 10, and to aid in positioning the strut so that its sharp point will rest on the block 8. There is also on the cover a stop 15 in the path of swing of the lever 11 and adapted, as will more particularly hereinafter appear, to cut

off the force of the weight 13 from the strut 10 and thereby prevent the valve from being held to its seat by the externally applied force.

Below the valve is arranged a thermo-responsive element or rod 16 which extends for a considerable distance downward into the hot water. Its free or movable end is seated in a slight depression or recess in the bottom face of the valve at its center while its other or anchored end is supported by a plate 17 fastened to the lower ends of two rods 18 which at their upper ends are secured to the wall of the device 3. The rods 18 are made of metal having a relatively low coefficient of expansion while the rod 16 is of highly expandable material.

With the several parts arranged as described and with the boiler under normal temperature and pressure conditions the valve remains seated. In the event of an abnormal pressure being generated in the boiler (and for the moment assuming no appreciable change in temperature) the force exerted internally on the valve 5 should lift it from its seat when said internal force overcomes the closing pressure applied to the valve through the strut 10. Thus one form of relief is provided by the device for excessive pressure alone. In case, however, someone has put additional weight on the lever 11, as by hanging some foreign article on the lever for the purpose of more tightly seating the valve (and thereby stopping what might have been a very slow leak), or if the bushing 14 binds too tightly on the strut 10 or corrosion has occurred there or at the pivot 12 all or any of which would prevent the strut from being pushed upward by the excessive pressure within the boiler, the device nevertheless provides relief because the pressure exerted from within can push the valve bodily against the strut 10. In so doing the sharp point of the strut penetrates the soft metal block 8. Thus another form of relief is provided for excessive pressure alone.

When there is no increase of pressure of any moment but the temperature is raised too high for safety the expandable rod 16 pressing on the valve can lift the strut and weighted lever and thus vent the system before any damaging pressure is generated, either by expansion of the water or by its conversion into steam. As before noted, if the strut cannot be moved the expanding rod 16 can force the valve and block upward about the strut and thus unseat the valve. In fact, it is just such a condition of increase of temperature that enables the function of the soft block 8 to be best utilized because the high temperature which causes the rod 16 to expand also serves to further soften the fusible block 8, making it even more susceptible to penetration by the sharp point of the strut.

And finally, if the strut cannot be moved,

or the anchor plate 17 has become loose from its supports, or the valve sticks to its own seat, any or all of which conditions might occur after a considerable lapse of time, the 5 fusible block 8 could melt and run through the branches in the valve, and the separate plugs 6 could fuse and thus open up several outlets through the valve for relief of the boiler.

- 10 While the different kinds of reliefs have been described separately for the purpose of making the several possible actions clear, it should be borne in mind that the operation of the different parts is by no means a series 15 of separate happenings. Whenever the valve and block 8 are raised, whether by pressure or temperature acting alone, there will be a slight penetration of the block by the pointed end of the strut. Of course most of the 20 movements of the valve are due to a combined change in pressure and temperature conditions and consequently almost every time the block is lifted it is at that time relatively soft and more easily penetrated by the strut. 25 Each time this occurs and the boiler has been relieved the valve will again tend to seat under the action of the weight 13. The bearing point, however, between the block and strut will be lower than initially owing to 30 the penetration of the block by the strut and consequently the strut will move to a lower position before brought to rest and the lever 11 will be nearer to the stop 15. After the device has operated a number of times the 35 cumulated penetration of the block by the strut will bring the lever to rest on the stop 15. When this occurs the valve of course will not be tight on its seat as will be evidenced by a leaking of the valve or by its 40 chattering. Either condition indicates need of attention and insures that the valve must be re-fitted with another block and put again into operable condition. This necessity of 45 keeping the device in workable condition is a factor in its favor because when once installed in a household it would ordinarily receive little attention and would be allowed to reach a condition where it would not provide the greatest safety for the boiler.

We claim:

1. A safety device for hot water boilers and the like comprising, in combination, a valve casing having an inlet adapted for connection with an outlet from the boiler; a discharge outlet from said casing in open communication with said inlet for service discharge of the boiler; a relief outlet from said casing; a pressure relief valve interposed between said relief outlet and said inlet having 55 a penetrable bearing on its external face; means holding said valve closed against normal water pressure and adapted to yield under excess pressure, having a member resting against said bearing and adapted to penetrate therein upon movement of the valve in 60

opening; and thermostatic means affected by the temperature of said water for opening said valve upon rise of said temperature beyond a predetermined degree.

2. A safety device for hot water boilers and the like comprising, in combination, a valve casing having an inlet at one end adapted for connection with the boiler; a discharge outlet in the side of said casing in open communication with the inlet for service discharge of the boiler; a relief outlet in the side of said casing beyond said discharge outlet; a valve seat arranged across said casing between said outlets; a valve on said seat shutting off said relief outlet from normal discharge having a hollow hub with penetrable metal therein; means comprising a member resting against said penetrable metal for holding said valve closed against boiler pressure and adapted to yield when said pressure exceeds a predetermined degree; and thermostatic means affected by rise of temperature of said water for forcing said valve against the said member of said holding means and thereby effect the opening of said valve. 90

3. A safety device for boilers and the like, comprising, in combination, a valve casing having an inlet adapted for attachment to an outlet from the boiler; a discharge outlet from said casing in open communication with said inlet; a relief outlet in said casing; a pressure relief valve cutting off said relief outlet from said inlet having a recess in its inner face; means holding said valve closed and adapted to yield under excess pressure in 100 the boiler; and thermostatic means responsive to temperature rise in said boiler, comprising a yoke extending through said inlet and boiler outlet into the boiler and an expansible bar having one end attached to said yoke and the other end resting in said recess of said valve and adapted upon expanding to lift said valve from its seat. 105

4. A safety device for a boiler comprising, in combination, a relief valve having a penetrable bearing on its external face; means applying external pressure to said valve comprising a member resting against said bearing and adapted to penetrate therein upon the valve being opened; and a stop arranged 110 to resist the pressure imposed by said means when said penetration has reached a predetermined limit consequent upon successive openings of the valve. 115

5. A safety device for a boiler comprising, 120 in combination, a relief valve having a hollow hub on its external face and holes leading therefrom to the internal face of the valve; a block of fusible metal in said hollow and said holes; means applying external pressure to seat said valve comprising a pointed member resting against said block; thermostatic means responsive to temperature change in said boiler arranged to apply an opening pressure on said valve to lift it from 125 130

its seat and effect a slight penetration of said member in said block, whereby upon re-seating of the valve the means applying the external pressure are nearer to the said valve;

5 and a stop interposed in the path of the last mentioned means limiting the extent to which said means can approach the valve whereby,

after a series of openings of said valve, said closing pressure is withheld from the valve.

In testimony whereof we have affixed our 10 signatures.

CHARLES A. TWIGG.
